UNITED STATES PATENT OFFICE

JOHN HINES, OF ASTORIA, NEW YORK, ASSIGNOR TO SEGAL LOCK & HARDWARE CO., INC., OF NEW YORK, N. Y., A CORPORATION OF NEW YORK

ACTUATOR

Application filed November 2, 1928. Serial No. 316,636.

This invention relates to an actuator or operating device to be primarily employed in connection with locks and latches.

It is an object of the invention to furnish a device of this character which may be employed as a substitute for a conventional knob and by means of which both a "door-pull" and lock-operating device are furnished, the entire unit being capable of being readily manipulated and, if desired, serving as a replacement part for a lock or latch installation made some time previously.

A further object of the invention is that of furnishing a device of this type in which no change on the part of locks—whether of the rim or mortise types—will be necessary in utilizing the actuator of the present invention, aside from the fact that by means of the present invention a device is furnished, the parts of which may be readily set to conform to varying conditions of installation.

An additional object is that of providing a lock or latch-operating device, the parts of which will be relatively few in number and individually simple and rugged in construction, these parts being capable of ready assemblage and application to a closure by means of unskilled labor so that minimum expense will be involved.

With these and further objects in mind reference is had to the attached sheet of drawings illustrating practical embodiments of the invention and in which:

Figure 1 is a partly sectional side view of an actuating device;

Fig. 2 is a rear view thereof;

Fig. 3 is an enlarged fragmentary view similar to Fig. 1, but showing a slightly different form of mechanism constructed within the province of the present invention;

Fig. 4 is a rear view of the parts as shown in Fig. 3, and

Fig. 5 is a perspective view of one of the elements forming a part of the assemblage shown in Figs. 3 and 4.

In these views no lock or latch mechanisms have been shown in that they are well-known to those skilled in the art and, generally stated, form no part of the present invention. Suffice it to say that in all types of locks and

latches it is customary to employ a spindle which is usually irregular in cross-section (as, for example, polygonal) and which cooperates with a bolt or latch-throwing mechanism regardless of whether the lock be of the mortise or rim type.

Thus, in the views afore-referred to, the numeral 10 indicates a spindle which may carry at its inner end a knob or other suitable actuating element 11. Adjacent the opposite end of this spindle a door plate 12 is provided which may be secured in any desired manner to a door and mounts the upper end of a handle 13 by, for example, having an opening through which this end of the handle passes and within which it is secured by having its inner end threaded and mounting a nut 14. The inner end of the spindle 10 is preferably reduced as at 15 and has bearing within a recess 16 formed in the handle, movement of these parts other than rotational being prevented as, for example, by a construction hereinafter brought out.

Adjacent its upper end the plate carries a pair of spaced lugs 19 pivotally mounting between them the inner end of a lever 20. This lever extends through an opening in the upper end of the plate and is formed with an angular portion 21 terminating in a part 22 to be engaged by the thumb or finger.

Mounted for sliding movement upon the inner face of the plate is a member 23 with arms 24 straddling the inner, upper end of the handle 13 and, furthermore, being provided with arms 25 extending beyond the lugs 19. In the crotch between these latter arms this member is formed with an outwardly extending portion 26, underlying the angular part 21 of the lever 20. This plate is retained against displacement as, for example, by the nut 14, it being observed at this time that the plate 12 has an inwardly extending flange 27 adjacent the opening through which the handle projects and which serves as a spacing element to prevent the nut coming into binding engagement with the member 23.

Finally, it will be noted that the spindle carries an arm 28 which extends into a recess formed in the edge of one of the arms 24 of the member 23 and a spring 29 normally

serves to force this member upwardly. Furthermore it will be noted that the flange 27 is interrupted as has been indicated at 17, and this interruption is in line with a slot 18 formed in the reduced end portion of the handle 13. By this construction the arm 28 may be passed through the spaces existing for this purpose and have its outer end bear within the recess of the arm 24. As a consequence, 10 a withdrawal of the spindle will be prevented and moreover, no extraneous securing means will have to be employed to retain the arm 28 in position.

As a consequence it will be appreciated 15 that as the handle is gripped and the thumb or finger-piece 22 is depressed, the member 23 will be moved downwardly against the influence of the spring 29, thus actuating the arm 28, which will rotate the spindle 10, thus 20 serving to actuate the lock or latch with which this member cooperates.

In the form of device shown in Figs. 3 to 5, the spindle 10 has its inner end mounted in a bracket 30, the arms of which mount between them a lever 31 extending through an opening in the plate 32 and which lever terminates in a thumb or finger-piece 33 and has an angular portion 34 bearing against an extension 35 riding within the plate opening 30 and forming a part of an operating member 36. This member is normally pressed upwardly as, for example, by a spring 37 and is retained properly disposed against the face of the plate as, for example, by means of a 35 nut 38 affixed to the inner end of the handle 13, which inner end, similarly to the form of construction shown in Figs. 1 and 2, projects through an opening in the plate and is prevented from coming into binding engagement with the member 36. Interposed between the operating member and the nut is a spring plate 39 terminating in a pair of arms 40 underlying those portions of the bracket 40 which extend beyond the point of pivotal 30 mounting of the lever 31, as a consequence of which the upper end of the bracket will always tend to swing inwardly towards the inner face of the plate 32, it being noted at this time that a pair of lugs 41 extend between 45 the arms of the bracket and the inner end of the lever and thus serve to retain the entire assemblage against displacement.

The pivotal mounting of the bracket and lever is, of course, effected by, for example, a pin 42 and the spindle carries at its inner end an arm 43 which rides within a transversely extending slot 44 formed in the operating member 36.

It will be apparent that with the parts assembled in this manner a depressing of the thumb or finger-actuator 33 will effectuate an oscillation of the spindle 10, the parts always being returned to normal position under the influence of the spring. If, now, it is found that the spindle 10 be not of proper size, this

may be remedied readily by simply withdrawing the pin 42 and associating with the assemblage a bracket carrying a proper size spindle. As a consequence a hardware dealer need not carry in stock a great number of complete units, but may carry in stock a suitable number of bracket elements carrying spindles of different sizes. Moreover, in certain types of locks (particularly of the cheaper class), it is always necessary to rock the spindle in one direction to cause a withdrawal of the latch or bolt. Thus, a locksmith may find that, as set up, the spindle rocks in the wrong direction. This may be quickly remedied by simply grasping the spindle and rocking the same downwardly to correspondingly move the bracket 30 to a point at which the arm 43 clears the slot 44. Thereupon, by turning the spindle to a point at which the arm 43 extends into the opposite end portion of the slot, it will be obvious that if actuation of the finger or thumb-piece is resorted to, the spindle will be rocked in an opposite direction.

From the foregoing it will be appreciated that, among others, the several objects of the invention are achieved. It will furthermore be understood that numerous changes in construction and rearrangement of the parts might be resorted to without departing from the spirit of the invention as defined by the claims.

Having described my invention, what I claim as new and desire to secure by Letters Patent is:

1. An actuating device including a plate, an operating member slidably mounted upon said plate, a lever rockingly connected to said plate, a rotatable spindle also connected to said plate and means coupling said operating member to said lever and spindle to convert the rocking movements of the former into rotational movements on the part of the latter.

2. An actuating device including a plate, an operating member slidably mounted upon said plate, a lever rockingly connected to said plate, a rotatable spindle also connected to said plate, means coupling said operating member to said lever and spindle to convert the rocking movements of the former into rotational movements on the part of the latter and means for normally forcing said plate in one direction to return said lever and spindle to predetermined positions.

3. An actuating device including a plate, an operating member slidably mounted upon said plate, a lever rockingly connected to said plate, a rotatable spindle also connected to said plate, means coupling said operating member to said lever and spindle to convert the rocking movements of the former into rotational movements on the part of the latter and means carried by said plate and spaced from said operating member to confine the

movements of the latter in a path adjacent the plane of the plate.

4. An actuating device including a plate, an operating member slidable with respect to the same, a lever connected to said plate and bearing against said operating member, a spindle also connected to said plate, an arm extending from said spindle and having operating connection with said member and said parts being arranged upon said lever being rocked to actuate said spindle.

5. An actuating device including a plate, an operating member slidable with respect to the same, a lever connected to said plate and bearing against said operating member, a spindle also connected to said plate, an arm extending from said spindle and having operating connection with said member and said parts being arranged upon said lever and being rocked to actuate said spindle, a handle mounted by said plate and extending through the same and means associated with the extended portion of said handle and cooperating with said member to confine the movements of the latter.

6. An actuating device including a plate, an operating member slidably mounted with respect to said plate, means disposed exteriorly of said plate and connected thereto to engage said operating member and shift the same, a spindle, an arm connected to said spindle, said operating member being formed with a slot accommodating said arm, and means for rotatably supporting said spindle with respect to said plate.

7. An actuating device including a plate, an operating member slidably mounted with respect to said plate, means disposed exteriorly of said plate and connected thereto to engage said operating member and shift the same, a spindle, an arm connected to said spindle, said operating member being formed with a slot accommodating said arm, a bracket for rotatably supporting said spindle, and readily detachable means for connecting said bracket to said plate.

8. An actuating device including a plate, an operating member slidably mounted with respect to said plate, means disposed exteriorly of said plate and connected thereto to engage said operating member and shift the same, a spindle, an arm connected to said spindle, said operating member being formed with a slot accommodating said arm, a bracket rockingly secured to said plate, and means bearing against said bracket for maintaining said arm within the area of the slot.

9. An actuating device including a plate, an operating member slidably mounted with respect to said plate, means disposed exteriorly of said plate and connected thereto to engage said operating member and shift the same, a spindle, an arm connected to said spindle, said operating member being formed with a slot accommodating said arm, a brack-

et for rotatably supporting said spindle, means for retaining said operating member immediately adjacent to said plate, and means forming a part of said last named means and acting against said bracket to maintain the arm carried by said spindle within the area of said slot.

10. An actuating device including a plate, an operating member slidably disposed with respect to the same and being formed with a slot, a spindle, an arm secured to said spindle and riding within said slot, said slot extending to both sides of a line intersecting the path of movement of said arm, and means for removably retaining said arm within said slot whereby it may be shifted to occupy a position adjacent either end of the slot.

11. An actuating device including a plate, an operating member movable with respect thereto, a spindle to be rotated in either direction upon movement of said member being effected, and means for selectively coupling said spindle to said member to cause clockwise and counter-clockwise movements of the spindle under identical movements of said operating member.

12. An actuating device including a plate, an operating member movably associated therewith, a spindle, means for coupling said spindle to said operating member, a lever, a support associated with said actuator, means for rotatably mounting said spindle, and a pivot common to said lever and said last named means for associating both of the same with said support.

In testimony whereof I affix my signature.
JOHN HINES.
